SPRINGING FOR RAILWAY TRUCKS

Charles D. Barrett and Charles R. Whitehead,
Altoona, Pa.

Application October 26, 1940, Serial No. 362,916

2 Claims. (Cl. 105—197.1)

This invention relates to springing for railway trucks and the like, and especially bolster trucks with leaf springs extending lengthwise in hollow bolsters. We have hereinafter explained the invention as applied in a truck of the general type disclosed in our Patent No. 1,199,907, granted May 7, 1940. Thus applied, the invention facilitates and cheapens the manufacture of the bolster and of the leaf springs, as well as the assemblage of the parts. Various other features and advantages of the invention will appear from the following description of species or forms of embodiment, and from the drawings. All the features and combinations described or shown are of our invention, so far as novel; and it will be understood that various such features or combinations may be used separately from the rest, and in trucks quite different from that here illustrated.

In the drawings, Fig. 1 is a fragmentary side view of a railway truck side frame showing the end of the bolster and the inner leaf springs within it, as well as a nest of coil springs under the bolster; Fig. 2 shows a partial longitudinal section through the bolster and the associated spring plank, taken as indicated by the line and arrows II—II in Figs. 3, the truck side frame appearing in cross section; Fig. 3 shows a horizontal section through the bolster, taken substantially just below its top wall; Fig. 4 shows a cross section through the bolster and leaf springs, taken substantially as indicated by the line and arrows IV—IV in Fig. 2, on a larger scale than the preceding figures; and Fig. 5 is a tilted view of the spring support which is shown in Figs. 2, 3, and 4, on a larger scale than Figs. 1-3.

Fig. 6 is a fragmentary sectional view of a portion of the bolster and an associated spring support, taken similarly to Fig. 2, but on a larger scale, and showing a modified construction; and Fig. 7 is a tilted view of the spring support shown in Fig. 6, on a larger scale.

In Figs. 1, 2, and 3, there is shown a cast steel truck frame 10 including the upper compression member 11, the lower tension member 12, and struts 13 interconnecting these members at either side of the bolster window, and providing guideways for the end of the hollow bolster 15, which has guide shoulders 16 to engage said guideways. There is also shown a spring plank 17 (of channel section) resting on the bottom 12 of the bolster window of the side frame 10, and connecting this side frame to the opposite side frame, not shown. In the bolster window

under the hollow bolster end is shown a group or nest of helical coil spring sets 18, 19, arranged in two fore and aft rows at opposite sides of the central vertical plane of the side frame 10,—though, of course, the number and arrangement of the springs may be varied as desired. Each spring set 18 or 19 is here shown as comprising oppositely wound inner and outer helical wire springs, nested one within the other. As shown, the springs 18, 19 are arranged substantially symmetrically with respect to the longitudinal central plane of the bolster 15, in the opposite sides of the bolster window. The larger spring sets 18 are shown with their upper ends engaged in corresponding circular recesses 21 in the lower side of the bottom wall of the bolster 15, while the smaller spring sets 19 are shown engaged around circular projections 22 on the bottom wall of the bolster. The lower ends of the spring sets 18 and 19 may be similarly or suitably engaged with a spring plate 23 which may rest on the spring plank 17 at the bottom of the bolster window, and may be interlocked with this spring plank by the usual projection and socket means (not shown).

As thus far described, the truck corresponds essentially to the standard A. A. R. side frame and bolster construction.

Inside the hollow bolster are leaf spring means 25, shown as multi-leaf semi-elliptic springs, which in the present instance act in parallel with the helical springs 18 and 19 under the bolster end. Two such multiple leaf springs 25, 25 are shown, arranged alongside one another at opposite sides of a longitudinal vertical web 26 in the outer end of the bolster 15, and extending substantially lengthwise of the bolster, but diverging from one another slightly from their closely juxtaposed inner ends outward toward the (open) outer end of the bolster. The web 26 interconnects the upper and lower walls of the bolster and thus strengthens it, and also forms separate compartments for the springs 25, 25. The springs 25, 25 may be attached to the bolster 15 by their inner end portions in such a way as to permit these portions to bend, while their outer ends are free in the bolster. As here shown, the springs 25, 25 bear upward against intermediate bearing seats 27, 27 on the upper wall of the bolster, about under its side bearing 28 and at mid-length of the springs, and they bear downward at their inner ends against a lower end bearing support 30, which will be further described hereinafter. Each upper seat 27 may have a concave cylindrical bottom surface

conforming to a cylindrical surface on the corresponding spring strap 31, and the sides of this strap 31 may fit loosely between bearing surfaces or pads 32 on the sides of the corresponding spring compartment of the bolster 15. The outer end of each spring 25 bears downward against a supporting member or saddle 33 inside the outer hollow bolster end, between upstanding side flanges 34 of this saddle. The bent outer end of each spring 25 engages and conforms to a fore and aft cylindrical-surfaced bearing ridge 35 on the saddle 33, whose axis may extend at right angles to the length of the spring, and very nearly in the fore and aft vertical central plane of the whole group of springs 18, 19, and of the side frame 10.

The bearing members or saddles 33 are preferably supported from the side frame 10 independently of the coil springs 18, 19, and preferably from the side frame member 12 at the bottom of the bolster window. As shown, these supporting members or saddles 33 rest on upright struts or columns 36 whose lower ends bear or rest against said member 12,—or, more properly, rest in sockets in a supporting plate 37 which itself rests on the spring plate 23 and has one or more bottom projections 38 engaged in one or more corresponding openings in the plate 23 and in the spring plank 17. The upper end of the struts or columns 36 extend loosely through openings in the lower wall of the bolster 15, and engage in shallow sockets in the lower sides of the saddles 33. Thus the outer ends of the springs 25, 25 are independently supported by different struts or columns 36, 36. The openings in the lower wall of the hollow bolster 15 may afford sufficient clearance around the struts or columns 36 to permit some movement of the members 33 transversely of the truck, as required by the slight bending of the springs 25 as the bolster 15 moves up and down. Thus the outer ends of the springs 25 do not rub across the cylindrical bearing surfaces 35 of the saddles 33, and wear at this point is minimized. As the coil springs 18, 19 act directly against the bottom of the bolster 15 and are quite stiff transversely of their own axes, they tend to stabilize the bolster transversely of the truck, thus reducing and minimizing the pressure or wear on the bolster guiding surfaces at 16 and 13. As here shown, the supporting struts or columns 36 are located in the longitudinal central fore and aft plane of the spring group and of the side frame 10, between the inner and outer fore and aft rows of springs 18, 19. As shown in Figs. 2 and 3, each bearing member or saddle 33 may have an upstanding ridge or lip 39 that coats with the bearing ridge 35 and with the down-turned end of the spring 25 to prevent endwise displacement of the part 33 relative to the spring 25, but does not interfere with the installation of the spring in the bolster. The bearing part 33 being connected to the outer end of the spring 25 and to the upper end of the column 36 as against relative displacement horizontally (by virtue of the socketed interengagement of these parts as above described), and the spring 25 being fixed longitudinally in the bolster (by its engagement at 30), it follows that the spring 25 controls the positions of the column 36 relative to the apertured lower bolster wall through which the column extends. The socketed engagement of the columns 36, 36 at the bottom of the side frame bolster window (in the openings of the parts 23, 17) contributes to the effectiveness of this control of the columns by the leaf springs.

The mode of operation of the structure illustrated and thus far described corresponds substantially to that disclosed in our Patent No. 2,199,907 above mentioned, especially Figs. 5 and 6. We will now proceed to describe the embodiment of our present invention (as here illustrated) in the lateral support 30 for the leaf springs 25, 25, at their inner ends.

As best shown in Figs. 3, 4, and 5, this support 30 comprises a separate transverse bar extending across the interior of the bolster between its side walls, and having its ends detachably mounted on these walls, preferably by socketed engagement with supporting means on the walls. For this purpose, the bolster side walls are shown provided with inward projecting lugs 40, 40, and the ends of the bar 30 have corresponding bottom recesses or sockets to fit over these lugs, each formed by downward projecting side lugs 41, 41 on the bar. As shown in Fig. 4, the bar 30 is spanned or bridged between the bolster side walls without any intermediate support. When the bar 30 is in place, its ends fit (with small clearance) between projecting pads 42, 42 on the bolster side walls; so that when putting the bar in place, there is plenty of clearance to permit moving the bar 30 about inside the bolster after its introduction thereto through suitable openings 43 in the bolster walls. Bearing means 44 for laterally engaging both springs 25, 25 may be removably mounted on the supporting bar 30, consisting as here shown of longitudinal liners or bars seated and engaged in corresponding grooves formed by lugs 46 upstanding from the top of the bar 30. The bar 30 may have an upstanding middle lug 47 that separates the inner ends of the leaf springs 25, 25, and coats with the side wall pads 42, 42 and with the mid-length engagement of the springs between the sides of their compartments at 32, 32 in aligning the springs in the bolster 15. In the present instance, there are separate bearing bars 44, 44 extending to either side of the lug 47; and as indicated in Fig. 5, they lie at a slight angle to one another and to the center line of the bar 30, so that each of them lies at right angles to the spring 25 which is engaged with it.

The construction illustrated in Figs. 6 and 7 differs from that in Figs. 2-5 in having the supporting lugs 48a, 48a on the sides of the bolster 15a socketed to receive the ends of the transverse bridge bar 38a, and in having the upstanding middle lug 47a on the bar 38a offset to one side, so that the groove in the bar 38a and the bearing bar or liner 44a extend past this lug from end to end of the bar 38a, without interruption. Furthermore, this form of support 38a can readily be made from a rolled steel bar by merely cutting off suitable lengths and welding the lug 47a to each such length; whereas the support 30 of Figs. 2-5 must be made as a special (die) forging or casting.

It will be appreciated that the use of our support 30 or 38a such as above disclosed materially reduces the cost of the bolster 15 or 15a, because it can be manufactured in the same way as standard A. A. R. bolster; whereas a bolster with an integral support across its interior for the inner ends of the leaf springs, as disclosed in our Patent No. 2,199,907, requires the use of an entirely different special system of cores in the molds for casting it. Furthermore, our construction does not require extreme accuracy as regards the relative heights of the leaf spring bearings 21, 21 and support 30 (or 38a) in the bolster and the camber

of the leaf springs 25, 25, because any minor inaccuracy can readily be taken care of by adjusting the thickness of the bearing bar or liner 44 or 44a to suit each case, thus assuring proper loading of the leaf spring in every instance.

Having thus described our invention, we claim:

1. The combination of a hollow truck bolster, a separate spring-supporting bridge bar spanned across the interior of said bolster, having its ends fixed to the bolster side walls against turning in the bolster, and provided with an upstanding middle lug, and also having its upper side longitudinally grooved, and a bearing bar extending

to either side of said lug, in the grooved upper side of said bridge bar.

2. The combination with a hollow truck bolster having internal supporting lugs on its side walls, and also having internal projections on said walls adjacent said lugs; of a separate spring-supporting bridge bar spanned across the interior of said bolster with its ends fitting between said projections and resting on said lugs, and in socketed 10 anti-turning engagement with the lugs.

CHARLES D. BARRETT.

CHARLES R. WHITEHEAD.
